FEELER MOTION FOR LOOMS.

1,413,784.

Specification of Letters Patent. Patented Apr. 25, 1922.

Application filed April 8, 1916. Serial No. 89,779.

To all whom it may concern:

Be it known that I, ALONZO E. RHOADES, a citizen of the United States, residing at Hopedale, county of Worcester, and State of 5 Massachusetts, have invented an Improvement in Feeler Motions for Looms, of which the following description, in connection with the accompanying drawings, is a specification, like characters on the drawings representing like parts.

The invention to be hereinafter described relates to feeler motions for looms, whereby upon detection of substantial exhaustion of the filling in the running shuttle, a train of 15 mechanism is rendered effective to change the operative condition of the loom as by replenishing the supply of filling.

The present invention relates more particularly to that type of feeler motions 20 wherein a feeler member receives directly upon it the forward push of the filling mass and is prevented from movement longitudinally of the shuttle until the filling has become substantially exhausted, whereupon 25 it is moved in a direction longitudinally of the shuttle by the forward push upon it to thereby position a train of mechanism for effecting replenishment of the filling.

As well understood by those skilled in the 30 art, a feeler mechanism must be sensitive and reliable in the discharge of its detecting function, in order that it will not call for a change of filling when a sufficient or working supply is present in the shuttle, and yet will detect 35 substantial exhaustion of the filling with accuracy and thereupon initiate the replenishing operation. When the filling is wound upon the filling carrier or bobbin, it is placed thereon by what is generally known as "a 40 filling wind," that is, the mass of filling is built up from the base portion of the bobbin in successive conical layers towards the end, so that the filling may be readily withdrawn from the shuttle. As it is thus drawn from 45 the shuttle during the weaving operation, the conical form of the wind is frequently presented to the feeler mechanism. Also, as is well recognized in the art, the longitudinal contour or shape of the wound mass of filling

50 varies greatly. The body of the completely-wound filling carrier or bobbin is generally of cylindrical form, but this general form varies according to the character of wind, as for instance, whether or not there be a 55 "bunch" placed upon the carrier or bobbin

and it also varies according to the usages of different mills. This variation in the cylindrical form may also result from other causes, and the longitudinal contour or shape of the bobbin itself frequently varies.

In view of the variations in the longitudinal contour of the surface that may be engaged, it is desirable that a feeler mechanism shall have a contact member or feeler tip that is self-conformable to the longitudinal shape 60 or contour of the surface within the shuttle engaged by it, whereby its working face may be permitted through contact with the filling mass or filling carrier to aline itself in parallelism with the longitudinal contour or surface of the portion of the filling mass or filling carrier presented to it. In feeler mechanisms of this general type, which are usually known as "side-swipe" feeler mechanisms, the laterally movable feeler member or arm 65 is held from movement laterally or in a direction longitudinally of the shuttle by engagement with the mass of filling when a working supply is present in the shuttle, but when the supply nears depletion and is too small to 70 prevent the lateral movement of the feeler member or arm, the engaging end or tip slides longitudinally of the filling carrier 75 along the engaged surface. Under both of these conditions it is desirable that the working face of the engaging member or feeler tip conform to the longitudinal direction and contour of the surface which acts against it regardless of whether such surface is the wound mass of filling or that of the filling 80 carrier or bobbin or even portions of both.

An important feature of the present invention, therefore, consists in a feeler mechanism wherein the engaging member or tip shall be self-conformable to the general longitudinal shape of the surface within the shuttle engaged by it so that it may be held from bodily longitudinal movement of the shuttle with accuracy by the filling mass 85 when a working supply is present, and be slid 90 longitudinally of the shuttle by the forward push upon it when the filling has become substantially exhausted.

In carrying this feature of the invention 105 into practical effect, the engaging member or tip is mounted for angular and bodily movements in a single plane so that when a working supply of filling is present, the engaging member or tip, upon engagement with a working supply of filling in the shuttle, may 110

conform itself to the general longitudinal contour or shape of the filling mass engaged by it and when such mass has become substantially exhausted, will be moved bodily 5 in the same plane and in a direction longitudinally of the shuttle to position a train of mechanism for effecting filling replenishment.

The above and other important features 10 of the invention will be hereinafter described, in connection with the accompanying drawings which illustrate a good practical form thereof, and then such features of the invention will be definitely pointed out by the 15 claims.

In the drawings:—

Figure 1 is a plan view of a feeler mechanism embodying the present invention, only sufficient parts of the loom being shown as 20 are desirable to make clear the association of the feeler mechanism therewith;

Fig. 2 is a view similar to Fig. 1, with some 25 of the parts omitted, showing the action of the feeler mechanism when a working supply of filling is present in the shuttle, and the lay makes its detecting beat;

Fig. 3 is a view similar to Fig. 2, showing 30 the action of the feeler mechanism when the supply of filling in the shuttle has become substantially exhausted and the critical point is reached at which replenishment is desired; and

Fig. 4 is a detached edge view showing 35 the relation of some of the parts of the feeler mechanism.

In the present illustrated form of the invention, the feeler carrier is mounted in a feeler stand 1 which may be secured to the loom frame in any suitable manner, as by 40 means of a slot 2 in an edge portion of the feeler stand through which suitable securing means may be passed, such as screws or the like. The feeler stand preferably comprises a base plate and a cover which may be of the usual well-understood construction, and such parts may be appropriately connected in 45 operative relation by the screws 3.

The feeler carrier 4 in the present instance 50 of the invention, comprises a sliding plate mounted in the feeler stand 1, for reciprocating movement. The feeler carrier 4 may be provided with a shank portion 5 extending through a suitable bearing in the front portion 55 of the feeler stand, and a wider portion 6 to slide upon suitable ways 7 formed in the feeler stand. A lug 8, shown by dotted lines in Fig. 1, and projecting downward from the cover of the feeler stand, may, in connection with an overhanging plate 9 to be further described, confine the feeler carrier 4 to 60 its longitudinal reciprocating movement with relation to the feeler stand. This formation of parts has been found to be convenient and practical, but it is to be understood 65 that the feeler carrier 4 may be variously

mounted, the essential in this respect being that the feeler carrier 4 shall have movement towards and from the front of the loom. In the present form of the invention, the feeler carrier 4 is normally held in its rearward position by means of a spring 10 which may be conveniently carried by the shank 5 with one end bearing against the inner front portion of the feeler stand and the other end against a suitable shoulder 11 75 formed on the feeler carrier.

The shuttle 12 may be of usual or any preferred construction, and in the present instance comprises the bobbin-holding jaws 13 adapted to receive between them the bobbin-holding rings 14 formed on the base portion 80 of the bobbin 15.

In the present feeler mechanism, the engaging member or tip feels into the shuttle on each detecting beat of the lay and receives 85 directly upon it the forward push of the surface or filling mass 16 therein; and in order that this action may be conveniently performed, the front wall 17 of the shuttle box is provided with an opening 18 and a similar 90 registering opening 19, is formed in the side wall of the shuttle, the construction being such that as the lay beats up, the feeler may enter the shuttle and feel for the filling therein. The construction so far described 95 may be as usual in this class of devices.

The present invention contemplates that the engaging member or tip which enters the shuttle on the detecting beat and feels for the filling therein, shall be self-conformable 100 to the general longitudinal shape or contour of the surface engaged by it in order that the engaging portion of the engaging member or tip may properly contact with an extended portion of the filling mass and be by 105 held from movement longitudinally of the shuttle when a working supply of filling is present on a detecting beat; but that such engaging member may be slid in a direction longitudinally of the shuttle by the forward 110 push upon it when the filling in the shuttle has become substantially exhausted. The engaging member or tip is, therefore, mounted for angular movement relative to the feeler arm which carries it, and in the present instance of the invention the engaging member or tip 20 is provided with a series of teeth, or roughened filling-engaging portions 21, and is pivotally mounted at 22 to a feeler arm 23 which has an offset pivotal connection at 24 with the feeler carrier 4, the construction being such that when a working supply of filling is present on a detecting beat the working surface or the toothed or roughened portions 21 of the engaging member or tip 20 will directly engage the working mass of filling in substantial parallelism to the longitudinal surface thereof and be held by said mass from movement longitudinally 125 of the shuttle as the lay completes its for- 130

ward movement. The effect of this is that should the longitudinal shape of the filling mass vary the filling engaging portion of the feeler member or tip 20 will conform to such 5 variations and shape and be effectively held by the filling mass from movement longitudinally of the shuttle.

In the present instance of the invention the rear end portion of the feeler carrier 4 10 is preferably recessed as indicated in Figs. 1, 2 and 3 of the drawings, and the engaging member or tip 20 is provided with a frontwardly-extending portion 25 loosely fitting said recessed portion of the feeler carrier to 15 permit such angular movement of the engaging member or tip 20 as above described. The construction in this respect is such that the walls 26 and 27 of the recessed portion of the feeler carrier 4 form stops against 20 which the edges of the frontwardly-extending portion 25 of the feeler tip may contact to limit both the swinging and bodily movements of the feeler member longitudinally of the shuttle. This form of construction 25 has been found convenient and practical, but it is to be understood that the invention is not necessarily restricted to these details.

The engaging member or tip 20 is pivotally mounted upon the feeler arm 23 which is uninfluenced by the angular movement of the 30 engaging member or tip as it conforms itself to the longitudinal shape or contour of the filling mass in the shuttle, but is movable with such engaging member or tip when the latter, upon substantial exhaustion of the filling in the shuttle, is moved longitudinally of the shuttle by the forward push. In the present instance, an actuator or lever 28 is pivotally mounted at 29 upon the feeler carrier 40 4 and has a recessed end portion 30 which is adapted at times to engage the end of a controller 31 as will presently appear. The other end portion of the actuating lever 28 is operatively connected to the feeler arm 23 by means of a pin and slot connection, such for instance, as a pin 32 projecting from the feeler arm 23 engaging a slot 33 formed in the end of the actuator 28.

It may be desirable in some instances to 50 limit the swinging movement of the feeler arm 23 as said arm carries the engaging member or tip 20 into its feeling position, as will presently appear; and to this end a pin 34 may be secured to the feeler carrier 45 4 to limit the movement of the feeler arm.

In order that the engaging member or tip 20 may be moved to its initial feeling position as the lay goes back after a detecting movement, the plate 9, hereinbefore 60 described, is provided with a cam portion 35 which is adapted to be engaged by the front end portion 36 of the actuator 28 and thereby turn the actuator and feeler arm to carry the feeler tip 20 into its feeling position as indicated in Figs. 1 and 2.

From the construction described, it will be apparent that when a working supply of filling is present in the shuttle on a detecting beat, the toothed filling engaging portion 21 of the feeler tip will directly engage the 70 filling mass and will automatically conform to the general direction of the longitudinal shape of the filling mass by swinging upon its pivotal connection 22 with the feeler arm; and as the lay beats up, said feeler tip 75 will be held from bodily movement longitudinally of the shuttle by said working supply of filling, and the parts will remain in the position indicated in Fig. 1, as they move with the feeler carrier 4 towards the front 80 of the loom, the end 30 of the actuator 28 at such times failing to engage the controller 31. When, however, the filling has become substantially exhausted as typified by Fig. 3, the forward push of the filling 85 carrier or bobbin against the feeler member 20 will cause the feeler tip to move bodily in a direction longitudinally of the shuttle as indicated in Fig. 3, thereby turning the feeler arm upon its pivot 24 and moving 90 the actuator 28 into the position for engagement of its end 30 with the controller 31 as the feeler carrier and feeler tip move further forward under the beatup movement of the lay. Such movement of the controller, substantially as indicated in Fig. 3, is utilized to set in operation a train of mechanism which may effect a change in the loom operation, as for instance, the filling replenishing mechanism, and cause such replenishment when the shuttle has returned to the replenishing side of the loom, as well understood by those skilled in the art. In order to return the controller 31 to its initial position again, as the feeler carrier 4 105 moves rearwardly after having initiated filling replenishment, the feeler carrier is provided with a lug 37 through which is threaded the adjusting screw 38, the end of which may engage the controller 31 as the feeler carrier 4 returns to its rearward position, substantially as indicated in Fig. 1. If desired, the adjusting screw 38 may be 110 provided with a set nut 39 which, when the screw is properly adjusted, may be set up against the lug 37 to hold the parts in their adjusted relation.

The rearward position of the feeler carrier 4 is controlled by suitable stops which in the present instance, comprise the edge portion 40 projected from the feeler carrier or slide, which is adapted to engage a stop 41 secured to the feeler stand when the feeler carrier 4 reaches its rearward initial position under the impulse of the spring 10. 120

Claims:

1. In a feeler mechanism for looms, the combination of a feeler arm which is mounted for movement toward the front of the loom and also in a direction longitudinally 130

of the filling carrier by the forward pressure when the filling is substantially exhausted on a detecting beat, a feeler tip having a plurality of filling engaging teeth which are moved longitudinally along the surface engaged by them when the filling is substantially exhausted, and pivotal connections between the feeler arm and feeler tip which permit the toothed engaging portion 10 of the feeler tip to conform to the surface of the filling carrier as the toothed surface of the tip slides longitudinally along the filling carrier.

2. In a feeler mechanism for looms, the combination of a feeler arm, a feeler tip which has a filling engaging toothed surface extending a substantial distance longitudinally along the surface engaged by it on a detecting beat and which is mounted on the 15 feeler arm for movement in three directions due to the forward pressure upon it on a detecting beat, one a movement toward the front of the loom, the second a movement longitudinally along the filling carrier when 20 the filling is substantially exhausted, and the third a movement to conform the extended toothed engaging surface of the feeler tip to the surface of the filling carrier as it slides longitudinally along the filling 25 carrier, and means actuated to effect replenishment of filling when the feeler tip partakes of its second movement due to the forward pressure upon it.

3. A feeler mechanism for looms, comprising, in combination, a feeler arm mounted for movement toward the front of the loom and for movement laterally, a feeler tip that is pivoted to the feeler arm and receives the forward pressure upon it to 30 effect forward and lateral movements of the feeler arm, and a series of teeth constituting the engaging end of the feeler tip and which slide along in conformation with the surface of the filling carrier or bobbin due to the forward pressure on the 35 feeler tip when the filling is substantially exhausted on a detecting beat.

4. In a feeler mechanism for looms, the combination of a feeler arm that is mounted for movement toward the front of the loom and also in a direction longitudinally of the filling carrier or bobbin by the forward pressure upon it on a detecting beat when the filling is substantially exhausted, a 40 feeler tip which is pivotally mounted on the feeler arm and has a plurality of teeth constituting the engaging end of the tip which slides longitudinally along the filling carrier due to the forward pressure when 45 the filling is substantially exhausted and which conform to the surface of the filling carrier as they slide along its surface, and means for effecting replenishment of filling when the feeler tip slides longitudinally 50

of the filling carrier or bobbin on a detecting beat. 65

5. A feeler mechanism for looms, comprising, in combination, a feeler carrier, a feeler arm mounted on the carrier for movement toward and from the front of the loom and also for movement longitudinally of the shuttle by forward pressure of a surface within the shuttle, a feeler tip having filling engaging teeth and pivotally mounted upon the feeler arm for bodily movement therewith toward and from the front of the loom and for pivotal movement relatively thereto and which conform to the surface of the filling carrier or bobbin as the feeler tip is moved longitudinally 75 along the surface of the filling carrier or bobbin when filling is substantially exhausted on a detecting beat.

6. A feeler mechanism for looms, comprising, in combination, a feeler carrier, a feeler arm pivoted on the carrier for movement toward and from the front of the loom and also for movement longitudinally of the shuttle by forward pressure of a surface within the shuttle, a feeler tip having filling 80 engaging teeth and pivotally mounted upon the feeler arm in lateral off-set relation to the pivot of the arm to cause movement of the arm and tip longitudinally of the shuttle by forward pressure upon the pivoted tip 85 and to conform the tip to the surface of the filling carrier or bobbin as the feeler tip is moved longitudinally along the surface of the filling carrier or bobbin when filling is substantially exhausted on a detecting beat. 90

7. A feeler mechanism for looms, comprising, in combination, a feeler arm which is pivotally supported for movement toward and from the front of the loom and also in a direction longitudinally of the shuttle, a feeler tip pivoted to the rear portion of the feeler arm in off-set relation to the pivotal support of the feeler arm that the forward pressure upon the feeler tip 100 may be effective to cause movement of the feeler arm in a direction longitudinally of the shuttle and conforming movement of the feeler tip to the surface of the bobbin or filling carrier as the tip moves along said 105 surface when filling is substantially exhausted on a detecting beat.

8. A filling-feeler of side-slipping type having the feeler-tip or contact piece thereof adapted for holding engagement with the filling-supply and for side-slip upon a substantially denuded filling carrier, and also movably hung in manner causing it to conform to the longitudinal direction and contour of the superficies of the shuttle-120 contents and make flat contact therewith in the feeling action and also as it slips laterally thereon. 125

9. A filling-feeler of side-slipping type comprising a laterally-movable feeler-member having a feeler tip or contact-piece adapted for holding engagement with the filling-supply and for side-slip upon a substantially-denuded filling-carrier, with said feeler-tip or contact-piece pivoted to the said feeler member so as to 20 permit self adjustment of the same on the feeler-member to the superficies of the shuttle-contents in a feeling action, and adapt its working face to slide in flat contact with the said superficies in the side-slipping ac- 25
thereon.

10. A filling-feeler of side-slipping type comprising a laterally-movable feeler-member having a feeler-tip or contact-piece
15

In testimony whereof, I have signed my name to this specification.

ALONZO E. RHOADES.
